CLAIM

The ornamental design for a combined tape player and radio, as shown and described.

DESCRIPTION

FIG. 1 is a top, front and left-side perspective view of a combined tape player and radio showing our new design;

FIG. 2 is a top, front and left-side perspective view thereof, shown in the open position;

FIG. 3 is a top, front and left-side perspective view thereof, shown with the antenna raised;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a top plan view thereof; and,

FIG. 9 is a bottom plan view thereof.
